United States Patent Office.

PETER ZIMMERMAN, OF DELAWARE WATER GAP, PENNSYLVANIA.

Letters Patent No. 79,717, dated July 7, 1868.

IMPROVED DEVICE FOR HANGING MILLSTONES.

The Schedule referred to in these Letters Patent and making part of the same.

TO ALL WHOM IT MAY CONCERN:

Be it known that I, PETER ZIMMERMAN, of Delaware Water Gap, in the county of Monroe, and State of Pennsylvania, have invented a new and useful Improvement in Apparatus for Hanging Millstones; and I do hereby declare that the following is a full, clear, and exact description thereof, which will enable others skilled in the art to make and use the same, reference being had to the accompanying drawings, forming part of this specification, in which—

Figure 1 represents a plan view of the bottom of my improved hanging-device, and

Figure 2 represents a partial section on the line xx of fig. 1.

Similar letters of reference indicate like parts.

The nature of my invention relates to improvements in apparatus for hanging running millstones, whereby it is designed to provide a means for accommodating the action of the spindle with reference to the stone, in case the spindle does not stand perpendicular to the face of the bed-stone; and it consists in the arrangement of a bail or suspending-apparatus for the stone, so as to possess the quality of a universal joint, whereby, although the face of the stones may not be perpendicular with the spindle, the jarring and pounding action of the parts, usually occurring when rigidly connected together, will be avoided, as will be more fully described on reference to the accompanying drawings.

A represents a bail, which is secured to the stone by the lugs A' A' in the usual manner, except that it is permitted to rock slightly in the recesses in the face of the stone, wherein the lugs A' and A' fit. The upper portion of the bail A terminates in a section of a cone, through which a circular opening, B, is formed, for the spindle to pass through.

Pivoted to the upper portion of the bail, at a a, is an auxiliary bail, C, provided with bent arms, D D, provided at their lower extremities with the set-screws b b, by which the amount of oscillation of the auxiliary bail, on the bail A, may be adjusted.

By this arrangement for hanging the running-stones, I am enabled to relieve the jarring and trembling of the same, caused by the ordinary manner of hanging, when it may occur that the bed-stone is not perfectly level, or if the spindle is not properly adjusted, or for any other reason.

Having thus described my invention, I claim as new, and desire to secure by Letters Patent—

The improved adjustable millstone-hanging device, substantially as herein shown and described, and for the purpose set forth.
